UNITED STATES PATENT OFFICE

MAURICE VINCENT BRESNAHAN, OF LYNN, MASSACHUSETTS, ASSIGNOR TO UNITED SHOE MACHINERY CORPORATION, OF PATERSON, NEW JERSEY, A CORPORATION OF NEW JERSEY

INSOLE-HOLDING DEVICE

Application filed July 19, 1928. Serial No. 293,911.

This invention relates to work positioning means for use in the manufacture of boots and shoes and is illustrated as embodied in a last having means for attaching an insole.

5 It has been the general practice heretofore in the manufacture of welt and other types of shoes to fasten the insole to its last by tacks, driven usually at the toe and heel ends and in the shank. There are, however, well known objections to the use of such tacks. It sometimes happens, for example, that a tack is left in the insole until the shoe is finished, and such a tack not only may cause injury to the wearer of the shoe but it is difficult 10 to remove and its removal may result in damage to the shoe. Since, moreover, the tacks are driven in about the same locations in the manufacture of different shoes on the same last, the wood of the last may finally become 15 so disintegrated that the tacks no longer hold effectively. Furthermore, with the prevailing practice, the accuracy with which the insole is positioned on the last depends entirely upon the operator's care and judgment.

20 25 In view of the foregoing, the present invention, in one important aspect, provides a last having novel means for positioning and holding insoles accurately in predetermined relation to the last bottom without the use of tacks. The construction illustrated comprises a last having a spring-metal clamping member permanently attached at one of its ends to the last bottom and extending forwardly along the last bottom. This member 25 is arranged to project through a hole in the insole and to hold the insole tightly to the last by pressure of the spring-metal member against the bottom surface of the insole.

30 40 Preferably, and as illustrated, a plurality of such clamping members are provided in convenient locations on the last bottom. In the use of the illustrated construction, when the last is pulled backwardly out of the shoe the forwardly extending spring members are 45 pulled back through the holes in the insole, releasing the last without difficulty.

These and other features of the invention comprising certain combinations and arrangements of parts will be apparent from 50 the following description of a preferred em-

bodiment of the invention shown in the drawings, in which

Fig. 1 shows the bottom face of a last embodying the invention;

Fig. 2 shows an insole attached to the last 55 of Fig. 1; and

Fig. 3 is a side elevation, partly in section, of the parts shown in Fig. 2.

The illustrated last 10 is intended for McKay shoe making and has the ordinary iron 60 bottom 12. Apertures 14, 14 are formed in the iron bottom 12 to permit the attachment of tongue-shaped spring insole retaining members 16, 16 to the wooden body of the last, by screws 18 passing through eyes in the 65 rear ends of the retaining members. Preferably, depressions 20 are formed in the last body in which to countersink the screw heads. From their points of attachment, the retaining members 16 have preferably a 70 slight S shape, bending outwardly at 22 away from the last bottom to a distance approximately equal to the thickness of an insole, then toward the bottom at 24, and finally 75 away from it again at 26, as best shown in Fig. 3.

An insole 28 to be attached to the last 10 is slotted or punched at locations corresponding to the first outward bends of the retaining members 16. In the attachment of the 80 insole the outwardly bent terminal ends of the retaining members are inserted in the holes in the insole which is then drawn backwardly into position on the last bottom, being held in place by the resilient pressure of 85 the retaining members, as shown in Fig. 3.

When the shoe is finished to the point where the last is to be removed, the last is easily pulled backwardly out of the shoe, the retaining members 16 slipping backwardly through 90 the holes in the insole, and releasing the last.

In the illustrated last two retaining members 16, 16 are arranged along the longitudinal medium line of the last bottom, one at the toe and the other in the shank portion, 95 but any convenient number, in any convenient location, may be used.

Having described my invention, what I claim as new and desire to secure by Letters Patent of the United States is:

1. A last having a resilient insole holding member attached by its rear end to the bottom of the last, and extending forwardly along the last bottom.
- 5 2. A last having a resilient insole holding member attached by its rear end to the bottom of the last, and extending forwardly along the last bottom in contact therewith.
- 10 3. A last having a plurality of resilient insole holding members attached by their rear ends to the bottom of the last, and extending forwardly along the last bottom in contact therewith, one of said members being located at the toe and another of said members being located at the shank, and all of said members being located in the longitudinal central line of the last bottom.
- 15 4. A last having an insole holding member attached to its bottom, said member consisting of a resilient tongue attached at its rear end to the last and bent first away and then toward the last whereby it may project through a previously prepared hole in an insole and press the insole against the last.
- 20 5. A last having a depression in its bottom surface and a resilient insole holding member with its rear end attached to the last in the depression and extending from its point of attachment first outwardly from the last bottom to a distance approximately equal to the thickness of an insole, then inwardly toward the last bottom, to enable it to hold resiliently an insole against the last bottom, and then outwardly again at its end to facilitate its insertion through a hole in the insole.
- 25

In testimony whereof I have signed my name to this specification.

MAURICE VINCENT BRESNAHAN.
